UNITED STATES PATENT OFFICE.

SAMUEL BARUCH, OF BROOKLYN, NEW YORK.

SHOE-TREE.

1,290,879.

Specification of Letters Patent. Patented Jan. 14, 1919.

Application filed April 10, 1918. Serial No. 227,670.

To all whom it may concern:

Be it known that I, SAMUEL BARUCH, a citizen of the United States and resident of Brooklyn, in the county of Kings and State 5 of New York, have invented certain new and useful Improvements in Shoe-Trees, of which the following is a specification.

This invention is an improved shoe tree adapted for use in stretching or forming 10 shoes, displaying them, holding them in proper shape while not in use or while being polished or cleaned. My improved construction is formed entirely of sheet material 15 cut and stamped or formed to the desired shape and the invention resides in certain important features of construction whereby greater durability, reduced cost of manufacture, and the improved operation is secured.

20 The shoe tree in its preferred form includes separate heel and toe parts, each of stamped material, preferably sheet metal, and a connecting spring strap rigidly secured at its ends. My improved heel part is 25 designed to fit the shoe not only up and down the rear seam but is readily adjustable to properly fit and support shoes of varying heel widths. The construction of this heel part as well as that of the toe part and the 30 means for connecting the spring involve novel and important parts of my invention. In the accompanying drawings I have illustrated one embodiment of my invention. Although it will of course be obvious that I 35 do not desire to be limited to the specific details of construction there shown.

In these drawings:

Figure 1 is a central longitudinal section through a preferred form of my shoe tree 40 in position.

Fig. 2 is a top plan view of the parts as shown in Fig. 1.

Fig. 3 is an inverted plan view of the toe part.

45 Fig. 4 is a rear end view of the toe part.

Fig. 5 is a development of the heel part before attachment to the connecting strip.

In the form illustrated the toe part is 50 formed of a single piece of sheet material, preferably sheet metal, which is cut and bent to form an arched top wall 10 and an approximately flat bottom wall 11, the two walls being connected together along the sides and front and being open at the rear, 55 in fact the toe part substantially conforms to the shape of the toe part of the shoe.

The bottom wall 11 has a slot 12 extending longitudinally thereof, and is cut away at the rear as shown particularly in Fig. 3. This permits an expansion or contraction of 60 the toe parts to fit different sized shoes, the sheet metal being preferably sufficiently annealed to permit the adjusting of the toe part to the desired width. Both the top and side walls may have perforations of 65 any desired size and number which may facilitate the drying out or ventilation of the interior of the shoe while the shoe tree is in place.

The heel part includes a substantially vertical plate portion 13 which is curved both vertically and transversely to conform generally to the rear of the shoe heel. 70

Integral with this plate are two wing portions 14—14 but the opposite vertical edges curve and extend forwardly along the sides of the shoe heel. These preferably are of less height than the year plate and are spaced above the sole of the shoe so as to engage only adjacent the upper part of the 80 vamp. These wings may be bent toward or away from each other to adjust the device to varying heel widths and when once adjusted will retain their form. To stiffen them and also to reduce the amount of metal in direct 85 contact with the inner surface of the shoe the wings are longitudinally corrugated or have portions 15 forced inwardly to a slight extent as indicated particularly in Fig. 2.

For connecting the toe and heel parts I 90 provide a spring steel strap 16 of such size and stiffness as to require bending as shown in Fig. 1 to permit the insertion of the shoe tree. When thus in place it tends to separate the toe and heel parts and hold the shoe 95 in proper form.

As an important feature of my invention I provide a top wall 10 of the toe part and the vertical plate 13 of the heel part with 4 transversely extending parallel slots of 100 slightly greater length than the width of the strap 16 and force inwardly the metal portions 17 between adjacent pairs of slots to form guides and retainers for the ends of the spring strap. At the toe part the strip is 105 inserted beneath the top plate 10, and above the two retainer portions 17 while at the rear the strap is inserted in front of the plate 13 and behind the retainer portion 17. In other words, in each instance the strap lies 110 along the surface of the plate away from the adjacent shoe surface. Between the 2 adja-

cent depressed retainer parts 17, the metal of the toe or heel part is forced downwardly or countersunk and within this countersunk portion is secured a rivet 19 which may extend through a suitable opening in the spring strap, thus only a single rivet is used at each end but the strap is firmly and rigidly held against endwise, lateral or turning movement. The connection of the strap to the shoe or heel part does not interfere with the presentation of a substantially smooth exterior surface for engagement with the shoe lining.

In the foregoing description I have referred to the device as a shoe tree but it will of course be evident that under the term shoe I intend to include slippers, boots, and all other forms of footwear.

The strap 17 may be made of various different lengths to suit different shoes and there may be if desired a series of holes adjacent to each end and through any one of which the rivet may be secured to give the desired length.

My improved shoe tree may be made in pairs as rights or lefts, form shown in Fig. 2 being for a left shoe. If desired, the toe pieces may be made symmetrical in respect to a central vertical longitudinal plane so as

to be freely interchangeable in right or left shoes.

Having thus described my invention, what I claim as new and desire to secure by Letters Patent is:

1. A shoe tree having a heel part formed of a sheet metal plate, curved vertically and transversely and having forwardly extending side wings spaced above the lower edge of said plate and corrugated lengthwise to re-inforce the same and a spring metal strap extending upwardly from said plate and having a portion parallel with and secured to the upper part of the rear or central portion thereof.

2. A shoe tree, having a heel part formed of a sheet metal plate, including a body portion curved vertically and transversely and forwardly extending wings at the side edges of said body portion with their upper edges constituting extensions of the upper edge of the body portion and having their lower edges spaced above and substantially parallel with the lower edge of the body portion.

Signed at New York city, in the county of New York and State of New York, this 9th day of April, A. D. 1918.

SAMUEL BARUCH.
